(57) **CLAIM**

The ornamental design for an earphone, as shown.

DESCRIPTION

FIG. 1 is a front elevational view of an earphone showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof.

1 Claim, 4 Drawing Sheets(56)
